DESIGN FOR A PLATE OR SIMILAR ARTICLE

Willis O. Prouty, Puente, Calif., assignor to Metlox
Manufacturing Company, Manhattan Beach,
Calif., a corporation of California

Application July 27, 1946, Serial No. 132,024

Term of patent 7 years

(Cl. D44—15)

To all whom it may concern:

Be it known that I, Willis O. Prouty, a citizen of the United States of America and a resident of Puente, in the county of Los Angeles and State of California, have invented a new, original, and ornamental Design for a Plate or Similar Article, of which the following is a specification, reference being had to the accompanying drawings, forming part thereof, in which:

Figure 1 is a top plan view of a plate or similar article, showing my design; and

Fig. 2 is a cross section thereof, taken as indicated by line 2—2 on Fig. 1.

I claim:

The ornamental design for a plate or similar article, substantially as shown.

WILLIS O. PROUTY.
